UNITED STATES PATENT OFFICE.

AUGUSTUS WASHINGTON WRIGHT, OF KYLE, TEXAS.

COMBINATION-WRENCH.

SPECIFICATION forming part of Letters Patent No. 341,117, dated May 4, 1886.

Application filed March 6, 1886. Serial No. 194,292. (No model.)

To all whom it may concern:

Be it known that I, AUGUSTUS WASHINGTON WRIGHT, a citizen of the United States, residing at Kyle, in the county of Hays and State of Texas, have invented a new and useful Improvement 5 in Combination-Wrenches, of which the following is a specification, reference being had to the accompanying drawings.

My invention relates to an improvement in 10 a combined nut-wrench, pipe-wrench, hammer, and screw-driver; and it consists in the peculiar construction and combination of devices, that will be more fully set forth herein-after, and particularly pointed out in the claim.

15 In the drawings, Figure 1 is a side elevation of my invention with the folding blade forming the screw-driver closed. Fig. 2 is an elevation of the same, partly in section, showing the screw-driver open.

20 A represents a bar of metal, which is fashioned so as to form at one end a nut-wrench, B. On one side of this wrench is formed a hammer-head, C. The opposite end of the bar is provided with a V-shaped opening, 25 forming diverging arms D, the opposing faces of which are notched or serrated, as at E, thereby forming a pipe-wrench, which is adapted to engage with pipes of different sizes. On the projecting end of one of the arms D is formed a screw-driver point, F. Near the center of the bar A, in one edge thereof, is made a longitudinal opening or slot, G, which is of suitable depth, and in one end of the said opening, at the bottom thereof, is seated a flat

spring, H, which corresponds in length to the 35 opening.

K represents a blade, which is pivoted in one end of the opening G, upon a pivotal pin, I, which extends transversely through the bar A, and the said blade bears on the free end of 40 the spring H, which thus serves to retain the blade in either an open or a closed position. The point of this blade forms a screw-driver, and the blade may be folded into the opening G when it is not desired to use it. 45

The combination-tool thus constructed is exceedingly cheap and simple, is very light and portable, and will be found of great convenience and utility.

Having thus described my invention, I 50 claim—

The bar A, having the nut-wrench and the hammer-head formed at one end, the pipe-wrench formed at the opposite end, and the slot G made in one side, the spring located in 55 the bottom of the slot or opening, and the blade pivoted in one end of the slot or opening and bearing on the free end of the spring, the said blade forming a screw-driver, substantially as described. 60

In testimony that I claim the foregoing as my own I have hereto affixed my signature in presence of two witnesses.

AUGUSTUS WASHINGTON WRIGHT.

Witnesses:

FRANK KEENAN,
B. S. NEIGHBORS.
